UNITED STATES PATENT OFFICE.

SWEBERT B. RIEG, OF MERIDIAN, MISSISSIPPI.

SAFETY APPLIANCE FOR RAILROAD-CARS.

1,143,648.

Specification of Letters Patent. Patented June 22, 1915.

Application filed March 17, 1915. Serial No. 15,033.

To all whom it may concern:

Be it known that I, SWEBERT B. RIEG, a citizen of the United States, residing at Meridian, in the county of Lauderdale and

5 State of Mississippi, have invented a new and useful Safety Appliance for Railroad-Cars, of which the following is a specification.

The present invention appertains to an 10 air brake applying device for railway cars, and aims to provide a novel and improved safety appliance for railroad cars, which is operable to open the air line under certain emergency or danger conditions, for quickly 15 bringing the train to a halt to avoid further danger or injury.

It is the object of this invention, to provide a safety appliance or attachment for railway cars, of such construction and operation, as to open the air line and allow the quick acting air brakes to be set immediately upon the happening of dangerous conditions, such as the derailing of a truck, the spreading or breaking of the rails, the 25 dropping of a brake beam, and the like, the invention also being adapted to be operated manually by the conductor or passenger of the train when a dangerous condition presents itself.

30 Another object of the invention is the provision of a safety appliance of the character specified, which will be operative under the various conditions, which will not become clogged or frozen up and thus impair its 35 utility, which is not liable to become rusted to cause the parts to stick or bind together when they should work loosely, and which is not liable to be broken or injured in operation.

40 A further object of the invention is the provision of a unique valve construction adapted to be interposed in an air line or train pipe and embodying a normally closed valve, and means for enabling the valve to 45 be opened when an emergency or danger condition arises.

It is also within the scope of the invention to provide a device of the character specified, which is comparatively simple, non- 50 encumbering and inexpensive in construction, which may be readily installed in railroad cars now in use, and which is simple, efficient and thoroughly practical in operation.

55 With the foregoing and other objects in view which will appear as the description

proceeds, the invention resides in the combination and arrangement of parts and in the details of construction hereinafter described and claimed, it being understood 60 that changes in the precise embodiment of the invention herein disclosed can be made within the scope of what is claimed without departing from the spirit of the invention.

The invention is illustrated in the accompanying drawing, wherein—

Figure 1 is a plan view illustrating a fragmental portion of a car truck, and the present appliance or attachment associated with the truck and air line or train pipe. 70 Fig. 2 is an elevation of the parts depicted in Fig. 1. Fig. 3 is an enlarged longitudinal section of the valve structure. Fig. 4 is a cross sectional view taken on the line 4—4 of Fig. 3. Fig. 5 is a detail view of the 75 link coöperating with one arm of the trip lever.

In carrying out the invention, there is provided a valve structure 1 embodying a T-shaped casing or coupling 2, adapted to 80 be interposed in the air line or train pipe. Thus, the sections 3 and 4 of the train pipe may be threaded or otherwise engaged into the ends of the casing 2. The arm or branch 5 of the casing 2 projects upwardly and the 85 casing 2 is disposed horizontally. The upper end of the arm or branch 5 is provided with a gasket 6 therein, and a valve 7 is pivoted, as at 8, to one side of the branch 5, and arranged to normally swing over the 90 said branch to close the same. The inner or lower side of the valve 7 carries a gasket 9 seatable upon the gasket 6, for providing a tight closure when the valve 7 is closed.

In order that the valve 7 may be normally 95 held closed, the free portion of the valve is provided with a lug 10 projecting therefrom, and the lug 10 is provided with an upper groove or notch 11. The upper face of the lug 10 is rounded or curved, as indicated at 12 in Fig. 4. That end portion of the casing 2 adjacent or nearest the free portion of the valve 7, is reduced in diameter, as at 13, and has journaled thereon a trip lever. This trip lever embodies a ring 105 or hub 15 journaled upon the reduced end portion 13 of the valve casing. The trip lever and valve casing are preferably constructed of iron, and to prevent the formation of rust therebetween, which would be 110 liable to cause the trip lever to stick or bind, the ring or hub 15 of the trip lever is pro-

vided with a copper or brass liner 16, and copper or brass collars 17 are threaded or otherwise engaged upon the reduced portion 13 of the valve casing at the opposite sides 6 of the ring 15 and for holding the trip lever in operative position.

The ring 15 has an upwardly projecting portion 18 provided with an angularly extending lug 19 overhanging the lug 10 of 10 the valve. The bottom of the lug 19 is provided with a ridge 20 for engaging the groove 11 of the lug 10. The ring 15 is provided with a depending arm 21 having a longitudinal bore 22 into which an adjusting screw 23 is threaded, and a detent 24 is slidable within the bore 22 and is engageable with a notch 25 provided in the reduced portion 13 of the valve casing for holding the trip lever in normal position. 15 A coiled wire expansion spring 26 is disposed within the bore 22 between the adjusting screw 23 and detent 24 for yieldably forcing the detent against the portion 13 of the valve casing, whereby the detent 24 will 20 snap into the notch 25 when the trip lever is swung to normal position. The engagement of the detent 24 with the notch 25 is such that the trip lever is normally held stationary, but is permitted to oscillate when 25 sufficient force is applied thereto. The ring 15 of the trip lever also has laterally projecting arms 27 and 28 at opposite sides and projecting away from each other.

The truck carries means for operating the trip lever when the truck is moved excessively relative to the car body, it being understood that the train pipe is carried by and below the bottom of the car body, whereby the truck in moving will move relative 40 to the train pipe and the valve structure 1. A member or shank 29 is secured to the bolster 29^a of the truck, and is provided with a fork 30 whose arms lie in a horizontal plane, and the arm 21 of the trip lever depends within the fork 30. The arms of the fork 30 are normally spaced from the arm 21, whereby the truck may oscillate the usual extent, as when rounding curves, without actuating the trip lever, but when the truck 45 oscillates laterally to an excessive degree relative to the body, one or the other of the arms of the fork 30 will contact with and swing the arm 21 of the trip lever for releasing the valve.

55 One of the arms of the fork 30 is provided with an outstanding portion 31 having an upturned portion or standard 32 provided with a U-shaped portion 33 receiving the arm 27 of the trip lever. The arm 27 projects within the U-shaped portion 33 and the said arm and portion may move relative to one another during ordinary conditions, without the trip lever being operated, but should the truck swing upwardly 60 or downwardly excessively relative to the

body, the upper or lower arm of the portion 33 will strike and swing the arm 27 of the trip lever to release the valve. The fork 30 and U-shaped portion 33 preferably open in the same direction, whereby they may be 70 readily drawn out of co-operative relation with the trip lever, without the liability of injuring the valve structure in doing so.

A slotted link 34 which is hung from a cable or flexible element 35 normally receives the 75 free end of the arm 28 of the trip lever, and the cord or cable 35 is passed over a pulley or guide 36 and may be connected to the brake beam, so that the falling of the brake beam will pull the cord 35 and raise the 80 link 34 sufficiently for swinging the arm 28. The cord 35 may also be extended to the vestibules or other portions of the train in order that the trip lever may be operated 85 manually by the conductor or passenger in the event of a dangerous condition being detected.

In operation, when the valve 7 is swung over its seat, it will seat itself, and then by swinging the trip lever, the lug 19 thereof, which acts as a detent element, will move over the curved face 12 of the lug 10, and will therefore press the gaskets 6 and 9 tightly together, and the ridge 20 of the lug 19 will then snap into the groove 11 of the lug 10 for holding the parts in place. At the same time, the detent 24 will snap into the notch 25 for holding the trip lever in normal position in connection with the engagement of the ridge 20 in the groove 11. 90 Under normal conditions, the trip lever or detent will not be actuated by the ordinary oscillations of the truck relative to the car body, but should the truck oscillate laterally excessively, such as when the truck becomes 95 derailed due to the spreading or breaking of the rails, the fork 30 will be swung sufficiently to one side for swinging the arm 21 of the trip lever. The trip lever being thus 100 swung, will disengage the detent lug 19 thereof from the lug 10 of the valve, and the valve will then be free to swing open. The air will therefore force the valve open, and in escaping from the train pipe will set the 105 automatic air brakes immediately for stopping the train. Should the truck swing vertically excessively relative to the body, due to the spreading of the rails, or the like, the U-shaped portion or member 33 will swing 110 the arm 27 of the trip lever to release the valve 7. If the cord or cable 35 is attached 115 to the brake beam, the dropping of the brake beam will pull the cord 35 and lift the link or member 34 to swing the arm 28 of the trip lever, and which will swing the trip lever to releasing position. The cord 35 may also 120 be extended to vestibules or other portions of the train, whereby it may be pulled by the conductor or passenger for opening the 125 safety valve.

Particular attention is directed to the fact that branch or arm 5 of the valve casing 2 projects upwardly, so that moisture and sediment cannot accumulate therein, and this 5 will prevent the valve structure from being clogged up or frozen. The device is also non-rusting, that is, a non-rusting engagement is provided between the valve casing and trip lever, whereby the trip lever is not 10 liable to stick or bind even though it is not moved for an extended period of time.

Having thus described the invention, what is claimed as new is:

1. In a safety attachment of the character 15 described, a valve structure embodying a T-shaped casing adapted to be interposed in a train pipe, a normally closed valve for the branch of the casing, and a detent embodying a ring journaled upon one end portion 20 of the casing and having a portion coöperating with the valve for holding the valve seated when the detent is in normal position.

2. In a safety attachment of the character 25 described, a valve structure embodying a T-shaped valve casing, the ends of which are attachable to the sections of a train pipe, a valve pivoted to one side of the branch of the casing, the branch having a valve seat, 30 and the valve being normally seated, and a detent embodying a ring journaled upon that end portion of the casing adjacent the free portion of the valve, the ring having a portion coöperating with the free portion of 35 the valve for holding the valve normally seated, and the ring having an operating arm projecting therefrom.

3. In a safety device of the character 40 described, a valve casing, a normally closed valve therefor, a detent carried by the valve casing for oscillatory movement and adapted to normally hold the valve seated, the detent having a plurality of arms projecting therefrom, and a plurality of actuating devices 45 coöperable with the respective arms of the detent whereby any one of said devices may swing the detent to valve releasing position.

4. In a safety attachment of the character 50 described, a valve structure embodying a casing and a normally seated valve, a trip

lever embodying a ring journaled upon the valve casing and having a plurality of arms projecting therefrom, the trip lever having means coöperable with the valve for normally holding the same closed, and a plurality of actuating devices coöperable with the respective arms of the trip lever whereby any one of said devices may operate the trip 55 lever.

5. In a safety device of the character described, a brake applying device adapted to be carried by a car body and including a trip lever having a depending arm and a laterally projecting arm, and a member 60 adapted to be carried by a car truck and having a portion into which the first mentioned arm of the trip lever depends, the said portion having an upstanding portion into which the laterally projecting arm of the 65 trip lever extends, said portions being arranged to normally move relative to said arms without swinging them and to swing said arms in the event of excessive movements of the truck.

6. In a safety device of the character described, a brake applying device adapted to be carried by a car body and including a trip lever having a depending arm and a pair of laterally projecting arms at opposite 70 sides, a member adapted to be carried by a car truck and having a horizontal portion receiving the depending arm of the trip lever, said portion having an upstanding portion receiving one of the laterally projecting arms 75 of the trip lever, and an actuating cord having means coöperable with the other laterally projecting arm of the trip lever whereby the trip lever can be swung when the cord is pulled, the said portions and respective arms 80 of the trip lever being normally movable relative to one another without swinging the trip lever and being designed to swing the trip lever in the event of excessive movements of the truck relative to the car body. 85

In testimony that I claim the foregoing as my own, I have hereto affixed my signature in the presence of two witnesses.

SWEBERT B. RIEG.
